UNITED STATES PATENT OFFICE.

ABRAHAM ZWIEBELSON, OF NEW YORK, N. Y.

CORSET.

1,414,245.

Specification of Letters Patent. Patented Apr. 25, 1922.

Application filed October 25, 1920. Serial No. 419,310.

To all whom it may concern:

Be it known that I, ABRAHAM ZWIEBELSON, a citizen of the United States, and a resident of the city of New York, borough of 5 Manhattan, in the county and State of New York, have invented a new and Improved Corset, of which the following is a full, clear, and exact description:

The invention relates to women's wearing apparel and its object is to provide a new and improved corset arranged to fit snugly around the wearer's body particularly at the diaphragm and under the bust to hold the flesh and ligaments in position without forcing the same out of place to the discomfort of the wearer.

Another object is to allow the wearer to move the body with the desired freedom and without unduly straining the same.

With these and other objects in view, the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is a perspective view of the improved corset as applied;

Figure 2 is an enlarged perspective view of the corset;

Figure 3 is an enlarged cross section of 35 the upper front portion of the corset; and

Figure 4 is a similar view of a modified form of the same.

The body 10 of the corset is practically of unbroken continuity and having a front 11 merging with the sides 12 and 13 connected with the back made in two parts 14 and 15 adapted to be fastened together by a suitable lacing 16 to close the corset at the back.

The front 11 is provided at the upper portion with a suitable stay 20 and the lower portion thereof is provided with a slit 21 adapted to be closed by a lacing 22 engaging eyelets 23 in the side walls of the slit, as plainly shown in Figures 1 and 2. Stays 45 25 and 26 are arranged at the junctions of the sides 12 and 13 with the corresponding back parts 14 and 15.

The upper edge of the front 11 and sides 12 and 13 is of approximately concave shape 55 by correspondingly cutting out portions of the material forming the front 11 and the

sides 12 and 13. An elastic member 30 extends across this cut-out portion and the elastic member 30 is preferably formed of elastic webbing made either of two pieces 60 31 and 32, as shown in Figures 1, 2 and 3, or a single piece of elastic webbing 33, as shown in Figure 4. If formed of two pieces of elastic webbing 31, 32 the two pieces are fastened together by a row of stitches 34 to 65 provide the desired width. The upper edge portion 40 of the front 11 and the sides 12 and 13 is formed by doubling up the body material as plainly shown in Figures 3 and 4, and to this portion 40 is fastened by two 70 parallel rows of stitches 41, 42 the elastic member 30. The upper edge of the elastic member 30 is provided with a binding 45, and the webbing 30 is held in stretched position during the time it is sewed to the 75 upper edge portion 40, and the binding 45 is sewed on so that on relieving the webbing of the tension the upper portion of the front 11 and the sides 12 and 13 of the body 10, and the binding 45 become gathered.

When the corset is donned and laced at the back, the elastic member 30 is placed under tension, and as the said elastic member extends around the front and the sides at the diaphragm and under the bust, it is 80 evident that the flesh and ligaments are held uniformly in position without forcing the same out of place to the discomfort of the wearer. It will further be noticed that by placing the elastic member 30 under tension 85 the corset is fitted snugly around the body without displacing portions thereof, at the same time allowing the desired freedom or bodily movement of the wearer.

It is expressly understood that the stays 90 are located only at the front and at the sides, and the elastic member 30 extends from one side stay to the other with the top edge of the elastic member in alignment with the upper edges of the back parts 14 and 15. It 95 is also understood that the ends of the elastic member 30 are secured in place at the junction of the sides 12 and 13 with the back parts 14 and 15.

It will be noticed that the upper concave 100 portion 40 terminates at its ends adjacent the top portions of the back parts 14 and 15 and as the portion of the elastic member projecting above the upper edge portion 40 gradually diminishes in width from the 105 middle to the ends of the said upper edge portion 40 it tends to hold the correspond-

ing portions of the wearer's body in proper position without danger of sagging.

Having thus described my invention, I claim as new and desire to secure by Letters

5 Patent:—

1. A corset having a concave upper gathered edge portion at the front and sides, of an elastic member attached to the said gathered edge portion and having its top approximately in alinement with the top of the back of the corset.

2. A corset comprising a body having a front and sides and having a back made in parts extending from the sides and provided with a lacing to fasten the back parts together, stays at the junction of the sides and back part, a stay at the front median line of the body, the upper edge of the body being approximately concave from side to side, an elastic band member and stitches fastening the lower edge of the band member to the said upper concave edge of the body, the band member being in stretched position while being sewed to the concave edge to gather the latter on relieving the band member of the tension, the upper edge of the band member being approximately in alinement with the upper edge of the said back.

3. A corset comprising a body provided

with a lacing at the back and having a front and sides, the upper edge of the body being concave from the median front line to the sides, and an elastic band attached at its lower edge to the body at the said concave edge, the top of the band being approximately horizontal and in alinement with the upper edge of the back of the corset.

4. A corset comprising a body having a front, sides and back, the latter being made in two parts, a lacing connecting the back parts with each other, the front having a laced slit at the lower portion and having a stay at the upper portion in alignment with the slit, stays at the junctions of the sides with the back parts, the upper edge of the body being provided with a cut-out portion extending from the front to the sides, an elastic member extending across the cut-out portion, and stitches fastening the elastic member to the edge of the cut-out portion at the time the elastic member is under tension to gather the body portion at said slit on relieving the elastic member of the said tension, the top of the elastic member being approximately in alinement with the top of the back.

ABRAHAM ZWIEBELSON.
